CLAIM

The ornamental design for a niche bracket, as shown and described.

DESCRIPTION

FIG. 1 is a perspective view of a first embodiment of a niche bracket showing my new design;

FIG. 2 is front plan view of the first embodiment;

FIG. 3 is a back plan view of the first embodiment;

FIG. 4 is a bottom elevation view of the first embodiment, the top elevation view being a mirror image;

FIG. 5 is a left side elevation view of the first embodiment, the right side elevation view being a mirror image;

FIG. 6 is a perspective view of a second embodiment of a niche bracket showing my new design;

FIG. 7 is a front plan view of the second embodiment;

FIG. 8 is back plan view of the second embodiment;

FIG. 9 is a bottom elevation view of the second embodiment;

FIG. 10 is a left side elevation view of the second embodiment, the right side elevation view being a mirror image;

FIG. 11 is a top elevation view of the second embodiment;

FIG. 12 is a perspective view of a third embodiment of a niche bracket showing my new design;

FIG. 13 is a front plan view of the third embodiment;

FIG. 14 is back plan view of the third embodiment;

FIG. 15 is a bottom elevation view of the third embodiment, the top elevation view being a mirror image;

FIG. 16 is a left side elevation view of the third embodiment, the right side elevation view being a mirror image;

FIG. 17 is a perspective view of a fourth embodiment of a niche bracket showing my new design;

FIG. 18 is a front plan view of the fourth embodiment;

FIG. 19 is back plan view of the fourth embodiment;

FIG. 20 is a bottom elevation view of the fourth embodiment;

FIG. 21 is a left side elevation view of the fourth embodiment, the right side elevation view being a mirror image;

FIG. 22 is a top elevation view of the fourth embodiment;

FIG. 23 is a perspective view of a fifth embodiment of a niche bracket showing my new design;

FIG. 24 is a front plan view of the fifth embodiment;

FIG. 25 is back plan view of the fifth embodiment;

(Continued)

FIG. 26 is a bottom elevation view of the fifth embodiment, the top elevation view being a mirror image; and, FIG. 27 is a left side elevation view of the fifth embodiment, the right side elevation view being a mirror image.
